UNITED STATES PATENT OFFICE.

JOHN LILLYQUIST, OF CHICAGO, ILLINOIS.

VALVE-STEM TRIMMER.

Application filed March 1, 1922. Serial No. 540,352.

To all whom it may concern:

Be it known that I, JOHN LILLYQUIST, a citizen of the United States, having residence in the city of Chicago, in the county 5 of Cook and State of Illinois, have invented certain new and useful Improvements in Valve-Stem Trimmers, of which the following is a specification, reference being had to the accompanying drawings forming a 10 part thereof.

The purpose of this invention is to provide a simple tool for trimming the ends of valve stems and for like operations without the use of elaborate guiding or steadyng means. It consists of certain features and 15 elements of construction hereinafter described and shown in the drawings as indicated by the claim.

In the drawings:—

20 Figure 1 is a side elevation showing the tool in position of use.

Figure 2 is a side elevation of the guide sleeve disconnected from the cutter.

25 Figure 3 is a side elevation of the shank and cutter with the guide sleeve removed.

Figure 4 is a side elevation of the part shown in Figure 3, as viewed in the transverse direction looking directly at the cutting edge.

30 Figure 5 is an end view of the cutter showing the guide sleeve in section.

It is well understood that when the valve seats of an internal combustion engine have been re-ground, it is necessary to re-adjust 35 the length of the valve stems in order that the valves may seat properly. In some engines no adjusting means is provided, and it is therefore necessary to trim off a small amount from the end of each valve stem.

40 In order to do this neatly the valve should be placed in a lathe or other machine designed for accurate work, or at least supported in a vise while the end of the stem is filed down. These methods, however, require either the relatively expensive tools 45 mentioned or considerable skill in the use of a file, and I have therefore designed the present tool for the use of the unskilled amateur mechanic to enable him to accomplish the work satisfactorily. The tool is not restricted to the particular use mentioned, but for purposes of illustration I have shown it as applied to this work.

In Figure 1 I have shown a valve, A, having the stem, B, whose end surface, C, is 55 to be cut away but left perpendicular to the axis of the stem, B. The tool comprises a shank, 1, adapted to fit in the chuck of an ordinary hand auger or brace indicated at 2, and a guide sleeve, 3, having a bore designed to fit closely over the stem, B, of the valve. The sleeve, 3, is removably attached to the shank, 1, by a headless screw, 4, which 60 engages a tapped hole, 5, in said shank so that the sleeve may be taken off to permit re-sharpening the cutter, 6, which is formed at the lower end of the shank, 1. The cutting edge 7, of the cutter, 6, extends radially from the axis of the shank, 1, and perpendicular thereto so that as the tool is rotated 70 against the end, C, of the stem, B, the cut will be made in a plane perpendicular to the valve stem axis. The surface of the cutter back of the edge, 7, is "backed off" for 75 clearance as indicated at 8 in Figure 3. 80 Adjacent the cutter the guide sleeve, 3, is provided with two openings, 9 and 9^a, which are diametrically opposite each other, but whose common axis is slightly oblique to the cutting edge, 7, so that the material cut away will be fed outwardly along the front face of the cutter, 6, and will escape through 85 said opening, 9. The opposite opening, 9^a, permits the user to observe the condition of the cutter and to clear out any chips more 90 readily than if a single opening were provided. The sleeve, 3, is elongated to extend for a considerable distance away from the cutting edge, 7, so as to secure a firm bearing upon the valve stem, B, and thus insure 95 an accurate job.

I claim:—

A tool for the purpose indicated comprising a shank formed at one end with a cutting edge perpendicular to its axis and substantially radial with respect thereto, together with a guide sleeve enclosing said cutting edge and bored transversely to form two openings at opposite sides of the sleeve respectively with their common axis slightly oblique to the cutting edge of the shank. 100

In testimony whereof, I have hereunto set my hand at Chicago, Illinois, this 29th day of October, 1921.

JOHN LILLYQUIST.
